[57] CLAIM

The ornamental design for a protective sheath for medical probe, as shown.

DESCRIPTION

FIG. 1 shows an elevation view of a protective sheath for a medical probe of my invention.

FIG. 2 shows an upper end view of the protective sheath of FIG. 1.

FIG. 3 shows a lower end view of the protective sheath of FIGS. 1-2; and,

FIG. 4 shows an elevation view of the protective sheath of FIGS. 1-3, the same as viewed in FIG 1, with dashed lines therein indicating surfaces of a blind hole which opens on the upper end of the sheath as seen in FIG. 2.
